INVENTOR

Abraham L. Adams
By his Atty.
Geo. Phillips

UNITED STATES PATENT OFFICE.

ABRAHAM L. ADAMS, OF BRIDGEPORT, CONNECTICUT.

EXPANSION-BIT.

SPECIFICATION forming part of Letters Patent No. 624,439, dated May 9, 1899.

Application filed July 22, 1898. Serial No. 686,639. (No model.)

To all whom it may concern:

Be it known that I, ABRAHAM L. ADAMS, a citizen of the United States, and a resident of Bridgeport, in the county of Fairfield and 5 State of Connecticut, have invented certain new and useful Improvements in Expansion-Bits, of which the following is a specification.

My invention relates to an improvement in expansion-bits; and it relates to the class of 10 rotary boring-bits known as "center bits," and particularly to center bits which are provided with adjustable cutters, wherein the tendency of the cutter unless prevented by positive means is to be forced forward under 15 the cutting strain, and thus enlarge the hole beyond the size for which the cutter was originally set. To counteract this tendency of the cutter to crawl, many expensive devices have heretofore been employed, which adds greatly 20 to the cost of manufacture, and thereby detracts very materially from the commercial value of the bit.

My improvement consists in tapering the base of the cutter in a gradually-diminishing 25 angle toward its cutting-point or nicker, so that when secured by its clamping-plate such angular formation will effectually prevent accidental movement under the cutting strain.

To enable others to fully understand my invention, reference is had to the accompanying 30 drawings, in which—

Figure 1 represents a front elevation of my improved bit, showing a broken view of the shank. Fig. 2 is a view similar to Fig. 1 with 35 the adjustable cutter and its clamping-plate removed. Fig. 3 is a similar view showing the adjustable cutter removed. Fig. 4 is a side elevation of the bit as shown at Fig. 1 looking in the direction of arrow *a*. Fig. 5 is 40 a side elevation of the bit as shown at Fig. 1 looking in the direction of arrow *b*. Fig. 6 is a detail bottom plan view of the adjustable cutter. Fig. 7 is a side elevation of the bit with the cutter removed, showing the cutter-seat 45 formed at right angles to the bit-head. Fig. 8 is a modified construction of the cutter, adapted to operate in the head shown at Fig. 7.

The construction and operation are as follows:

1 represents the shank of the bit, and 2 its head, which head is provided with the slot or

seat 3 to receive the clamping-plate 4 and the base of the adjustable cutter 5.

6 is the clamping-screw.

The seat 3 in the head 2 is formed in one cut 55 or operation by means of an ordinary rotating cutting-tool, so that the edges 8 and 9 will receive the proper undercut, as shown at Figs. 4 and 5, while such edges will extend across the face of the head at an angle with the shank, 60 as shown at Fig. 2, and at the same time be parallel with each other.

The beveled edge 5^a of the bit rests against the edge 9 of the seat 3, while the angle of the opposite beveled edge 5^b is more acute, making the rear end 5^c of the adjustable cutter wider than the forward end 5^d, thereby forming the base of the cutter tapering or wedge-shaped.

The beveled edge 4^a of the clamping-plate 70 4, Fig. 3, is of course the same taper or angle as the edge 5^b of the cutter, so that in shifting the cutter all that is necessary is simply to loosen the screw 6 and move the said cutter in either direction required. In this case, 75 where the cutter is provided with the wedge-shaped base, the screw will have to be turned back a trifle more than ordinary in order that the clamping-plate may have a greater vertical movement to compensate for the wedge-shaped formation of the cutter. The clamping screw and plate will easily hold the cutter down, while its wedge-shaped formation will effectually prevent its being drawn forward in the only direction it is liable to be 80 accidentally moved under the cutting operation.

In the modification shown at Fig. 7 the side walls 8^a and 9^a of the seat 3 are formed at a right angle to the axis of the bit instead of being angularly disposed thereto, as in the other views. The forward or binding lip 4^a of the clamping-plate would have the same angular formation as shown in the other views, and the bit, Fig. 8, would have the same angular 95 formation 5^b to engage therewith, while the opposite edge 5^f will be straight to engage the straight edge 9^a, Fig. 7, of the seat of the bit.

From the foregoing description it will readily be seen that my improvement has a decided advantage over cutters that are provided with teeth and pinions to prevent lon-

itudinal displacement, and this advantage does not lie wholly in economy of construction, which of itself is of vital importance, but it is also capable of closer adjustment.

5 Having thus described my invention, what I claim as new, and desire to secure by Letters Patent, is—

1. The herein-described improvement in expansive bits consisting of a cutter provided 10 with a wedge-shaped base whereby the forward end of said base is made narrower than its rear end to prevent accidental displacement of said cutter under the cutting strain said cutter having a beveled edge combined 15 with a clamping-plate having a beveled edge adapted to engage with the beveled edge of said cutter substantially as described and for the purpose set forth.

2. The combination, in an expansive bit of 20 the character described, of the head 2 provided with a cutter-seat whose side walls are formed parallel to each other, the cutter 5 having the angularly-formed beveled edge 5^b so as to leave the front end 5^a of said cutter 25 narrower than its rear end 5^c, the clamping-

plate 4 whose cutter-engaging lip 4^a is also beveled to correspond to the beveled edge of said cutter and tapered to the same pitch or angle as the angularly-disposed edge 5^b of the cutter, substantially as set forth.

3. The herein-described improvement in expansion-bits consisting of a cutter whose base is made narrower at the forward or cutting end than at its rear end, combined with a head portion whose forward end wall is angularly disposed, a clamping-plate whose forward end is of an opposite taper to the said end wall of the head, thus making the side supports for the said cutter to correspond to its angularly-disposed edges said cutter and 40 clamping-plate having correspondingly-beveled engaging edges, substantially as described and for the purpose set forth.

Signed at Bridgeport, in the county of Fairfield and State of Connecticut, this 30th day 45 of June, A. D. 1898.

ABRAHAM L. ADAMS.
